E. H. DURU Inventor

United States Patent Office.

EUGÈNE HIPPOLYTE DURU, OF PARIS, FRANCE.

Letters Patent No. 71,720, dated December 3, 1867; patented in France, October 25, 1867.

IMPROVED CAR-BRAKE.

The Schedule referred to in these Letters Patent and making part of the same.

TO ALL WHOM IT MAY CONCERN:

Be it known that I, EUGÈNE HIPPOLYTE DURU, of Paris, in the Empire of France, have invented a new and useful Improvement in Railway-Brakes; and I do hereby declare that the following is a full, clear, and exact description of the construction and operation of the same, reference being had to the annexed drawings, making a part of this specification, in which drawing—

Figure 1 is a rear end view in elevation of a wagon with this new brake fixed to it.

Figure 2 is a partial side view of the same.

Similar letters indicate corresponding parts.

A is the handle to set the tension-roller or windlass into motion. B is a windlass or tension-roller, on which wind the chains or cords, which tighten the jaws of the pincers. In the middle of this roller is fixed a cord or rope, N, by means of a hook, which cord or rope serves to raise up the pincers as soon as slackened. C C are the pincers, the lower extremities of which fit the rails. C' C' are the jaws of the pincers. D D are boxes containing the pincers. E E are slide-blocks to maintain the pincers on a level with the upper part of the rail, whatever may be the variations occasioned by the loading of the cars. F F are pulleys, serving to guide the chains or ropes. G G is the apparatus to maintain the whole tight, as may be required. I I are springs to open the jaws. K is the hand-wheel on which the handle A is secured. M is a chain or rope connecting this hand-wheel with the pincers at the opposite end of the car. The pincers C consist, like ordinary pincers, of two arms or jaws, which open by means of springs, and close by means of chains working in an inverse direction, so as to compel the machine to bite the head of the rail, and may be so constructed as to avoid the obstacles resulting either from joints or from the railroad-chairs. In view of this the jaws C' are scooped out so as to avoid every impediment that might occasion a shock. The pincers C are contained in the iron box D, fixed at the lower cross-piece or at the bottom of the car, and steadied by an iron bar, to insure solidity. The pincers C receive their movement from the handle A, placed at the upper part of the vertical cylinder or windlass B, on which wind the chains or ropes of the pincers C, by passing on the pulleys F, as also a third chain fixed at the central point of the pincers C, which serves to elevate them when the brake is slackened. This chain, less stretched than the others, winds on the windlass in an inverse direction, and it serves to keep the pincers constantly on a level with the heads of the rails, whatever movements or variations of level may occur in the loading of the cars. The pincers may be directly actuated by the engineer, by means of a chain or rope, M, wound round the hand-wheel K. The slide-block E, held in position by a fork, fixed at the central point of the pincers, is placed behind them, which lifts and lowers with them, as may be required, through an opening made in the box D of the pincers, as shown in the accompanying drawing. To prevent the pincers from experiencing any side shocks in consequence of the back-lashing of the cars when in motion, it is merely necessary to give a little freedom to the chains or ropes. Underneath the handle A is a ratchet-wheel, for the purpose of tightening the brake.

From what has been said it is easily understood how rapid is the means of tightening, and the action is such that a train running at full speed may be stopped without a shock within a comparatively short length of rail, so that the meeting of trains may be avoided, and the danger to the travelling public is materially reduced. This kind of brake possesses, moreover, a great advantage over any other, viz, that of preventing the train from running-off the track. The jaws biting the heads of the rails, necessarily retain the train in an upright position. Two of these brakes to each train will fully replace the old brakes.

What I claim as new, and desire to secure by Letters Patent, is—

The adjusting-gear B F N, in combination with the pincers C and with a railroad-car, substantially as and for the purpose set forth.

E. H. DURU.
